UNITED STATES PATENT OFFICE.

ARTHUR R. MOSLER, OF NEW YORK, N. Y.

SPARK-PLUG.

1,186,221.

Specification of Letters Patent. Patented June 6, 1916.

Application filed August 12, 1914. Serial No. 856,426.

To all whom it may concern:

Be it known that I, ARTHUR R. MOSLER, a citizen of the United States, and resident of the borough of Manhattan, in the city and State of New York, have invented a new and useful Improvement in Spark-Plugs, of which the following is a specification.

The object of my invention is to provide a spark plug which will be very simple in construction, cheap to manufacture and gas-tight.

A further object is to provide certain improvements in the construction, form and arrangement of the several parts whereby the insulator is permanently locked in position within its shell by a single locking ring introduced through the inner end of the shell and permanently forced out of its original shape, said ring being composed of a metal such as aluminum having a greater coefficient of expansion than the metal of which the shell is made.

A practical embodiment of my invention is represented in the accompanying drawings, in which—

Figure 1 represents the shell, the insulator, the outside packing ring and the inside locking ring, in longitudinal central section, the inside locking ring being in the position which it assumes before it is forced into position for locking the parts together, Fig. 2 is a longitudinal central section through the spark plug showing the positions which the parts assume after the locking ring has been forced into position for locking the insulator to the shell, and Fig. 3 is a similar view showing a slightly modified form in which the use of a recess in the shell for receiving a portion of the locking ring, is obviated.

The hollow shell is denoted by 1 and it is provided with an annular seat 2 formed by an inwardly directed annular flange 3 at its outer end. The bore 4 of the shell is cylindrical and the shell may be provided with the usual externally screw threaded portion 5.

The insulator is denoted by 6 and is provided with a flange 7 intermediate its inner and outer ends, which flange forms an inner shoulder 8 and an outer shoulder 9, which shoulder 9 is opposite the seat 2 of the shell 1. A packing ring 10 is interposed between the shoulder 9 and seat 2.

The shell 1 is provided with a recess 11 in its bore 4, which recess is herein shown

as an annular groove adjacent to the shoulder 8 of the flange 7.

The locking ring 12 is composed of some material, such as aluminum, which has a greater coefficient of expansion than the metal, such as steel, of which the shell 1 is composed. This locking ring 12 has a tapered bore 13 and a cylindrical exterior surface, said cylindrical exterior surface having a sliding fit within the cylindrical bore 4 of the shell. This tapered bore of the locking ring 12 gives the walls of the ring 12 a wedge shape, thus permitting the ready insertion of a portion of the ring between the flange 7 of the insulator and inner wall of the shell 1.

In assembling the parts, the insulator is inserted through the inner end of the shell with the washer 10 interposed between the shoulder 9 and seat 2. The locking ring 12 is then inserted through the inner end of the shell, into the position shown in Fig. 1. The insulator and shell is then placed in the die of a press and a suitable tool, such as a ring-shaped punch is introduced through the inner end of the shell into engagement with the locking ring 12 forcing the same out of its original shape and causing the ring to wedge itself between the flange 7 of the insulator and the inner walls of the shell, and, at the same time, filling the recess 11. At the same time the packing ring 10 at the outer end of the shell is compressed thus locking the insulator permanently to the shell with the exterior of the insulator spaced from the shell.

In Fig. 3 I have shown no recess 11. In this form, the wedging action of the locking ring between the insulator and the inner walls of the shell is depended upon for the permanent locking of the insulator to the shell.

After the insulator has been locked to the shell, the electrode 14 may be inserted through the insulator and held in its position with the usual nuts 15 and 16. It is also provided with the binding nut 17.

It is evident that slight changes may be resorted to in the form, construction and arrangement of the several parts without departing from the spirit and scope of my invention; hence I do not wish to limit myself strictly to the structure herein shown and described, but

What I claim is:—

1. A spark plug comprising an insulator

- having a circumferential flange, a shell and means introduced through the inner end of the shell and forced between the flange and shell for permanently spacing the insulator 5 from and securing it within the shell.
2. A spark plug comprising an insulator having a circumferential flange, a shell and a wedge-shaped ring introduced through the inner end of the shell and forced between the flange and shell for permanently spacing the insulator 10 from and securing it within the shell.
3. A spark plug comprising an insulator having a circumferential flange, a shell and a wedge-shaped ring of metal having a greater coefficient of expansion than the metal of the shell, introduced through the inner end of the shell and forced between the flange and shell for permanently spacing the insulator 15 from and securing it within the shell.
4. A spark plug comprising an insulator, a shell having a recess in its bore and means introduced through the inner end of the shell and forced between the insulator and shell and into said recess for permanently securing the insulator 20 within the shell.
5. A spark plug comprising an insulator, a shell having a recess in its bore and a wedge-shaped ring introduced through the inner end of the shell and forced between the insulator and shell and into said recess for permanently securing the insulator 25 within the shell.
- 30 6. A spark plug comprising an insulator, a shell having a recess in its bore and a wedge-shaped ring of metal having a greater coefficient of expansion than the metal of the shell, introduced through the inner end of the shell and forced between the insulator and shell and into said recess for permanently securing the insulator within the shell.
- 35
- wedge-shaped ring of metal having a greater coefficient of expansion than the metal of the shell, introduced through the inner end of the shell and forced between the insulator 40 and shell and into said recess for permanently securing the insulator within the shell.
7. A spark plug comprising an insulator having a shoulder, a shell having a seat and a recess in its bore, a packing interposed between the shoulder and seat, and a wedge-shaped ring introduced through the inner end of the shell and forced between the insulator and shell and into said recess for 45 permanently securing the insulator within the shell.
8. A spark plug comprising an insulator having a shoulder, a shell having a seat and a recess in its bore, a packing interposed between the shoulder and seat, and a wedge-shaped ring of metal having a greater coefficient of expansion than the metal of the shell, introduced through the inner end of the shell and forced between the insulator 50 and shell and into said recess for permanently securing the insulator within the shell.
9. A spark plug comprising an insulator having a shoulder, a shell having a seat and a recess in its bore, a packing interposed between the shoulder and seat, and a wedge-shaped ring of metal having a greater coefficient of expansion than the metal of the shell, introduced through the inner end of the shell and forced between the insulator 55 and shell and into said recess for permanently securing the insulator within the shell.
10. In testimony, that I claim the foregoing as my invention. I have signed my name in presence of two witnesses, this tenth day of August 1914.

ARTHUR R. MOSLER.
